UNITED STATES PATENT OFFICE.

ELLIS S. ROYER, OF BISMARCK, MISSOURI.

CASE-LOCK.

No. 918,374.

Specification of Letters Patent.

Patented April 13, 1909.

Application filed June 20, 1906. Serial No. 322,604.

To all whom it may concern:

Be it known that I, ELLIS S. ROYER, a citizen of the United States, residing at Bismarck, in the county of St. Francois, State 5 of Missouri, have invented certain new and useful Improvements in Case-Locks; and I do hereby declare the following to be a full, clear, and exact description of the invention, such as will enable others skilled in the 10 art to which it appertains to make and use the same.

This invention relates to watch case locks, and has for its object to provide a device of this class which will securely hold the front 15 and back of a watch against removal unless released by a proper form of key.

A further object of the invention is to provide a lock of this character which will automatically spring into place and lock 20 without the necessity of the insertion of a key.

With the above and other objects in view, the invention consists in the construction, combination and arrangement of parts, all 25 as hereinafter fully described, and pointed out in the accompanying drawings, in which—

Figure 1 is an edge view of a watch casing showing the device applied thereto. Fig. 2 30 is a similar view showing the casing broken away. Fig. 3 is a detail sectional view on the line 3—3 of Fig. 2. Fig. 4 is a view similar to Fig. 2, showing a slightly modified form of lock.

Referring more specifically to the drawings, the numeral 5 denotes the case center of a watch case, 6 the front bezel thereof, and 7 the lock. At any desired point in its periphery the case center 5 is recessed, as at 35 8, and secured in the recess by means of screws 9 is a plate 10, which is arcuate in form to conform to the curvature of the case center 5. Pivoted, as at 11, to the plate 10 is a pair of locking bolts 12, which include 40 each portions 13 and 14, which extend at an obtuse angle to each other, as shown in Fig. 2 of the drawings. The locking bolts hence lie at acute angles with respect to each other, and the portions 13 each have their ends 45 turned laterally, as at 15, for normal engagement through openings 16 in the walls of the recess formed in the case center of

the watch and into notches formed in the edges of the front and back of the watch case. The bolts are normally held in this 55 position by means of a spring, as will be presently explained, and in order to permit the front and back of the case to be screwed into place and automatically lock, one wall of the notch 17 in the front and back is 60 beveled, as at 18, in a direction opposite to the direction of rotation of the front and back of the case when screwing the same into place. The spring mentioned above is in the form of a bowed leaf spring 19, 65 which has its ends turned inwardly toward each other, as at 20, and engaged with lugs 21 formed at the ends of the bolts 12 opposite their laterally bent ends 15, the tendency of the spring being to normally move the 70 said ends of the bolts toward each other and force their opposite ends through the openings 16 and into the notches 17. A key-hole 22 is formed in the said case center for the engagement therethrough of a key 75 23, which has oppositely extending wards 24 which serve to spread the ends 14 of the bolts 12, when the key is turned, thereby releasing the bolts from engagement with the front and back of the case. The key-hole 80 22 is preferably formed through a barrel 25, which is formed integral with the case center of the casing and is provided with a screw dust-cap 26, which prevents entrance of dust into the casing. 85

In the form of my lock shown in Fig. 4, there is shown a bolt 27, which is pivoted, as at 28, at one of its ends, and has its opposite end turned, as at 29, for engagement 90 through the case center and into the recesses formed in the front and back of the casing, a second bolt 30 is pivoted at or adjacent its middle to the plate 10 and is connected at its end opposite its laterally turned end to the bolt 27 by means of a link 31. 95 Springs 32, which are secured at one of their ends to the plate 10 bear with their free ends against the bolts 27 and 30, and normally hold the same in locking position. The key used with this form of lock has but 100 one ward 33, which engages the bolt 30 and serves to withdraw the said bolt and the bolt 27 from locking engagement with the front and back of the casing.

What is claimed, is:—

1. In a watch, the combination with a case center and a screw bezel, of a key operated bolt for holding the bezel against removal.
2. In a watch, the combination with a case center and front and back screw bezels, of bolts supported upon the case center for holding the bezels against removal and ar-

ranged to be simultaneously operated by a single key.

In testimony whereof, I affix my signature, in presence of two witnesses.

ELLIS S. ROYER.
